BROACHING MACHINE

Leo I. Kaplan and Bror Gustaf von Reis, Detroit,
Mich., assignors to Detroit Broach Company,
Detroit, Mich., a corporation of Michigan

Application August 25, 1938, Serial No. 226,780

12 Claims. (Cl. 90—33)

This invention relates to broaches for cutting splines on a male shaft member and also to the fixtures for supporting the broaches on a broach machine.

An object of the invention is to provide means for broaching splines on the exterior of a shaft along the entire length thereof, the broaching operation constituting the only and, hence, the finishing operation in the formation of the splines.

It is also an object to provide means for broaching separated groups of splines in the exterior sides of a shaft of any shape in cross-section along the entire length thereof in one operation, the shaft blank having finished ground arcuate corners and/or a finished bore longitudinally thereof constituting locating means for the broaches.

More particularly it is an object to provide means for simultaneously broaching a plurality of sides of a shaft blank in such manner that peripherally separated groups of splines are formed thereon, the intervening spaces of the blank or the longitudinal bore being employed as locating means, and to provide alternate forms of broach holders such that the locating means may be relatively movable or relatively fixed with respect to the blank.

Another object is to provide an improved tool holder or fixture to cut splines along the length of a shaft characterized by means for holding the shaft blank from opposite sides while cutting two other sides and reciprocal on or with a broach machine table to and from cutting position, the holder positively holding the blank during cutting operations and automatically releasing its hold on the blank when the tool is retracted.

A further object is to provide means for positively holding a shaft blank, as above described, in combination with means for indexing said blank for cutting the remaining sides when the pressure on the first two sides is relieved.

Other objects and advantages will become more fully apparent as reference is had to the accompanying drawings wherein our invention is illustrated and in which:

Fig. 1 is a top plan view of our improved fixtures with a shaft blank inserted therein in position for the initial cutting operation, the broach machine slides being shown in section.

Fig. 2 is a view similar to Fig. 1 showing also the broaches and completion of the first cutting operation.

Fig. 3 is a view similar to Figs. 1 and 2 showing

completion of the second cutting operation;

Fig. 4 is a vertical section taken along the line 4—4 of Fig. 2;

Fig. 5 is a detail section taken along the line 5—5 of Fig. 4;

Fig. 6 is a detail section taken on the line 6—6 of Fig. 1;

Fig. 7 is a top plan view of a modified form of tool holder and cutters,

Fig. 8 is a vertical section taken along the line 8—8 of Fig. 7 showing the cutters immediately above the blank, the blank being partially broken away;

Fig. 9 is an end elevation of the blank;

Fig. 10 is a vertical section of a modified fixture;

Figs. 11 and 12 are sections taken respectively on the lines 11—11 and 12—12 of Fig. 10; and

Fig. 13 is a section, similar to Fig. 12, and illustrating the work positioned for the second cutting operation.

More particularly 1 indicates a stationary table of a broaching machine upon which a work holding fixture platform 2 is slidably mounted. A work holding fixture is keyed at 4 to the platform 2, and is composed of a large block 3 having two work-holding rods 5 slidably mounted therein.

Each of the rods 5 has a work-gripping end 6 normal thereto for engaging a work piece 7 in order to hold the piece against an oppositely placed holding member 8 carried by the block 3. The two work holding means 6 and 8 thus grip the work piece, which in this instance is a shaft blank, along two opposite side walls thereof. It is contemplated, in Fig. 4, that the broaches 9 will approach the work 7 from above and hence a base member 10 is also provided at the lower end of the work to oppose the thrust of the broaches 9, this member 10 being supported on the lower one of the rods 5. The other ends of the rods 5 are pivotally connected, jointly, to a toggle device which consists of links 11 each pivotally connected at one end to an arm 5 and each pivotally connected at 12 to a further link

13 which in turn is pivotally anchored at 14 to a standard 15 rigidly mounted on the machine 1. The connections 12 are pivotally connected to links 16 which are mutually pivoted at 17, and between this connection 17 and the standard 15 a spring 18 is inserted.

The operation is as follows: the fixture 2, 3 is slid to the left, Fig. 4, for loading; the spring 18 reduces the angle between the arms 16 pulling the connections 12 toward each other to main-

tain pressure of the fingers 6 on the work until the fixture has travelled a considerable distance. Further retracting movement of the fixture is accompanied by sliding of the shafts 5 in the block 3 and consequent lateral separation of the members 6 and 8. The work piece 7, being hollow, is then inserted between the members 6 and 8 and placed on the base in engagement with a tightly fitting or expansion type extension 19 integral with the base 10. The fixture is then traversed to the position illustrated in Fig. 1, whereupon the shafts 5 slide in the block 3, thus closing the members on the work while positioning the work immediately below the broaches 9. The broaches are then actuated through the work taking opposed cuts of two groups of splines 20, as illustrated in Fig. 2. The work is then indexed and the broaches take a second cut of the remaining two surfaces, as illustrated in Fig. 3.

Any suitable indexing means may be employed, one suitable type being illustrated in Figs. 4, 5 and 6. The base 10 is mounted on a shaft 21 which is journaled in the lower rod 5. A ratchet gear 22 is fixed to the bottom of the shaft 21 for engagement by a spring pressed pawl 22a pivotally mounted on a bracket 23 which is fixedly mounted on a stationary part of the machine 1. The pawl 22a is placed so that it will rotate the base 10 and work 7 through ninety degrees as the fixture approaches its retracted position. The work 7 does not shift laterally with respect to the clamping member 6 and hence the member 6 has a cut-out portion 24 formed on an arc of a circle having the same radius as that of the corners 25 and 26 of the work piece.

The work piece is of generally rectangular shape in plan view, with the corners rounded and formed on the arc of a common circle. The four corners 25, 26, 27 and 28 are first ground to accurate shape, the intervening or connecting surfaces 29, 30, 31 and 32 being flattened. Since the arcuate corners are finished ground before placement of the work piece in the broaching machine 1, they are reliable guide and locating means and are employed as such. The clamps 6 and 8 are provided with arcuate regions to receive these arcuate corners so that when the clamps are drawn together the broaches will then cut surfaces having an exact and known relation with the corner surfaces. The shafts are then cut or broached throughout their entire lengths and no further operation, such as hobbing, is necessary.

Figs. 1 to 5 illustrate clamps which are stationary, whereas Figs. 8 and 9 illustrate a base support for the work and guide or locating surfaces which travel with the broaches. The work blank 33 is placed on a support 34 analogous to the support 10, previously described. Four broaches 35 joined by corner pieces 36 are then clamped together ready for traversal through the work. The broaches 35 each has a series of spline cutters thereon and these cutters are separated by the accurately formed arcuate surfaces 37 on the blocks 36. As the broaches travel over and through the work the surfaces 37 closely fit the arcuate surfaces 38 and constitute locating means to maintain correct relative position of the broaches and the work.

In the modified fixture shown in Fig. 10, a stationary table 40 has a work holding fixture platform 41 slidably mounted thereon. A work holding fixture 42 is keyed at 43 to the platform 41, and has a single work holding rod 44 which is slidably mounted therein. The slideable rod 44

has a work-gripping formation 45 for engaging a work piece 46 adjacent one end thereof, whereby the pressure of a spring 47, acting on toggle links 48, which are connected to the rod 44, causes the work-gripping formation 45 to hold the work piece 46 against an oppositely disposed work holding member 59.

As described in conjunction with Figs. 1 to 5, it is contemplated that the broaches will approach the work from above, and the rod 44 is, therefore, provided with a base member 49 at the lower end of the work to oppose the thrust of the broaches. The base member 49 is rotatable, and has a ratchet wheel 50 connected thereto and adapted to be rotated by a pawl as 15 above described for indexing the work piece. The base member 49 has a tightly fitting or expansion type extension 49a extending into the lower end of the work piece 46.

In the work fixture 42 is slidably mounted a pin 51, accurately located with respect to the work holding member 59, and adapted to project into the upper end of the work piece 46 to hold it against the work holding member 59. Linkage 52 is connected to the pin 51 for the purpose of retracting it from contact with the work piece, and for replacing it in contact with the work piece.

The work-gripping formation 45 and the work holding member 59 both have arcuate surfaces 30 for engaging the work piece 46, which is of circular section. The work piece is finished ground before placement in the broaching machine, and the broaches first cut the splines 53 indicated in dotted lines in Fig. 12 and full lines in Fig. 13. The work is then rotated through ninety degrees, after which the broaches cut the second series of splines shown in dotted lines in Fig. 13.

What is claimed is:

1. A fixture for holding a work blank in a broaching machine having reciprocable broaches comprising a base reciprocable toward and away from the direction of travel of the broaches, a work blank support on said fixture, work locating means for gripping the blank along the length thereof, and automatic means responsive to the movement of said base toward the line of travel of said broaches drawing said means together to impose substantial pressure on said blank during cutting travel of said broaches along said blank.

2. A fixture for holding a work blank in a broaching machine having reciprocable broaches comprising a base reciprocable toward and away from the direction of travel of the broaches, a work blank support on said fixture, work locating means for gripping the blank along the length thereof, and automatic means responsive to the movement of said base toward the line of travel of said broaches drawing said means together to impose substantial pressure on said blank during cutting travel of said broaches along said blank, said automatic means responding to withdrawal of said base from said line of travel to release the pressure of said locating means from said blank.

3. The combination of a broaching machine, an endwise support for a work blank on said machine, reciprocable broaches grouped for simultaneously taking a plurality of peripherally spaced cuts along the exterior of said blank, and non-cutting means separating said broaches and movable therewith and constituting guides for contacting said blank throughout the cutting operation along the spaces between said cuts.

4. The combination of a broaching machine, an

endwise support for a work blank of generally rectangular transverse cross-section having rounded corners, broaches for simultaneously cutting splines in a plurality of the sides of the blank, and work locating means active along the length of said rounded corners retaining said blank in correct cutting position.

5. The combination of a broaching machine, an endwise support for a work blank of generally rectangular transverse cross-section having rounded corners, broaches for simultaneously cutting splines in all of the surfaces between said rounded corners, and work locating means movable with said broaches and contacting said rounded corners during the cutting operation.

6. The combination of a broaching machine having reciprocable broaches, a support for a work blank on said machine, a plurality of guides peripherally spaced about said blank and residing along the sides thereof supporting said blank during the entire reciprocation of said broaches thereover, said guides gripping said work blank during travel of the broaches over said work, means releasing said guides from pressure contact with said blank, means indexing said blank after release of said guides and means automatically returning said guides to work gripping position after indexing.

7. A fixture for holding a work blank in a broaching machine having reciprocable broaches comprising a base reciprocable toward and away from the direction of travel of the broaches, a work blank support on said fixture, work locating means for gripping the blank along the length thereof, automatic means responsive to the movement of said base toward the line of travel of said broaches drawing said means together to impose substantial pressure on said blank during cutting travel of said broaches along said blank, said automatic means responding to the withdrawal of said base from said line of travel to release the pressure of said locating means from said blank, indexing means operative to partially rotate said blank after the initial cutting operation by said broaches after the release of the pressure from said blank.

8. A fixture for holding a hollow work blank in a broaching machine having reciprocal broaches, comprising internal positioning abutments shaped to fit into and engage the internal surfaces at opposite ends of the work blank and to extend circumferentially around at least a major portion of such surfaces for contact with a multiplicity of diametrically opposed points, an abut-

ment for engaging the work blank externally, and means for causing relative movement between at least one internal abutment and the external abutment whereby said abutments grip the work blank therebetween.

5

9. A fixture for holding a hollow work blank in a broaching machine comprising a base reciprocal toward and away from the broaches, a pair of oppositely disposed abutments for engaging and clamping one end of a work blank on said fixture, said abutments being movable toward and away from the work blank incident to movement of the base toward and away from the path of the broaches respectively whereby the abutments grip and release the work piece, and a 10 movable abutment for engaging the work blank and adapted to hold the same in contact with one of said first two abutments during movement of the base.

10. A fixture for holding a work blank in a 20 broaching machine comprising a base reciprocal toward and away from the path of travel of the broaches, means on said fixture for supporting a work blank for rotative movement about its longitudinal axis, automatic means for rotatively 25 moving the work blank incident to movement of the fixture away from the path of the broaches, and means rendered operative by travel of the fixture toward the path of the broaches for 30 clamping the work against rotative movement.

11. The combination of a broaching machine having a set of broaches relatively reciprocal with respect to a work support, said work support having an abutment adapted to engage in one 35 end of a work blank to position the blank with respect to the broaches, said set of broaches comprising circularly grouped units adapted to act on all sides of the blank simultaneously, and means for causing relative movement between the broaches and the support.

12. The combination of a broaching machine having a set of broaches relatively reciprocal with respect to a work support, said work support having an abutment adapted to engage in one 40 end of a work blank to position the blank with respect to the broaches, said set of broaches comprising circularly grouped units adapted to act on all sides of the blank simultaneously and having guide means engaging the blank to hold the blank and broaches in predetermined position 50 during relative movement between the broaches and the blank.
